(57) CLAIM

The ornamental design for a massage oil warmer, as shown and described.

DESCRIPTION

FIG. 1 is a front, left and top perspective view of the first embodiment of a massage oil warmer, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, left and top perspective view of the second embodiment of the massage oil warmer;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The broken lines shown in the drawings illustrate portions of the massage oil warmer that form no part of the claimed design.
